UNITED STATES PATENT OFFICE.

ALEX A. CLARKE, OF DALLAS, TEXAS.

MOTOR-DRIVEN SURFACE-TREATING MACHINE.

Original application filed February 13, 1920, Serial No. 358,485. Divided and this application filed January 22, 1921. Serial No. 439,185.

To all whom it may concern:

Be it known that I, ALEX A. CLARKE, a citizen of the United States, residing at Dallas, in the county of Dallas and State 5 of Texas, have invented certain new and useful Improvements in Motor-Driven Surface-Treating Machines, of which the following is a specification.

This invention relates to new and useful 10 improvements in motor driven surface treating machines.

This application is a division of my application filed February 13, 1920, Serial No. 358,485.

15 The invention has to do with the economic and practical arrangement of the various parts, whereby simplicity and efficiency is had.

20 The object of the invention is to provide a housing structure conducive to quantity production and in carrying out the invention various novel features are evolved, together with certain mechanical expedients which make for a finished product.

25 A construction designed to carry out the invention will be hereinafter described together with other features of the invention.

30 The invention will be more readily understood from a reading of the following specification and by reference to the accompanying drawings, in which an example of the invention is shown, and wherein:

35 Fig. 1 is a side elevation of a machine constructed in accordance with this invention.

Fig. 2 is a plan view of the same.

Fig. 3 is a central vertical sectional view

of the machine.

40 Fig. 4 is a partial longitudinal vertical sectional view,

Fig. 5 is a sectional detail of one of the vertical adjusting posts and component parts,

45 Fig. 6 is a sectional detail of the drum and sleeve fastening means, and

Fig. 7 is a detail of the adjustment locking means.

50 In the drawings the numeral 10 designates an upright rectangular frame having outwardly directed brackets 11 at its top and bottom at each side. At the center of the bottom of each end of the frame a collar 12 is fastened and receives the ends of fixed shaft 13 on which a ball bearing cone 14 is 55 mounted to receive near each end, ball bear-

ings 15 confined in ball races 16. The ball races 16 are secured to the inside of end plates 17 forming parts of the drum 18. The drum 18 is surrounded by a sheet 19 of sand paper or other suitable material for 60 abrading work. As is shown in detail in Fig. 6 the sand paper 19 has its ends fastened in a depression 20 in the surface of the drum by means of a bar 21 and screws 22, which bar in practice has its outer surface inward from the surface of the sleeve formed by the sand paper so as not to engage the surface worked upon.

65 Within the upper portion of the frame a motor chamber 23 is formed and this chamber is preferably circular in cross section with its top wall 24 projecting upward from the frame. The fields 25 of a motor are mounted in this chamber which extends transversely of the frame the same as the 70 drum. At one end of the chamber a mounting plate 26 is inserted and properly fastened. This plate has apertures 27. An armature 28 is mounted within the field 25 and has a shaft 29 which engages in a ball 80 bearing 30 in the plate 26 and at its opposite end in a ball bearing member 31 which is carried by a mounting plate 32 having apertures 33. A fan 34 is mounted on the armature 28 and is revolved thereby. This 85 fan sets up a circulation of air thru the apertures 27 and 33 thereby cooling the motor which is a very important and essential feature.

90 A spur gear 35 is mounted on the armature shaft and meshes with a pinion 36 mounted on a bracket 37 and projecting thru the bottom wall of the chamber 23. This pinion 36 meshes with and drives a gear 38 fastened to the drum 18. It will be 95 seen that the drum is driven by means of a gearing direct from the motor shaft. It will also be noticed that the ends of the drum are reduced in diameter so as not to mar the work. It is pointed out that the 100 whole arrangement is compact and simple.

105 The frame is mounted upon vertical posts 38 with their lower ends fastened to a base 39. As shown in detail in Fig. 5 the upper portion of each post is screw-threaded and receives a sprocket 40 which is threaded thereon. Each sprocket 40 bears on the top of the frame and is confined by an arm 41 extending from the top wall 24. An endless sprocket chain 42 passes over all of the 110

sprocket wheels 40 and is tightened by means of a belt tightener 43 mounted on one of the brackets 11 on top of the frame. Between the brackets at one side of the frame a tubular handle 44 is mounted while in the other two brackets a tubular handle is mounted. The lower end of the handle 44 is confined within a flange member 46 secured to the lower bracket 11; while the upper 10 end is confined in a similar flange member 47 so that the handle may be rotated. A plug 48 as is best shown in Fig. 4 is secured in the upper end of the tubular handle and projects upward thru the top bracket 11 and has 15 fixed thereon a sprocket wheel 49 over which the chain 42 also passes. It will be seen that by rotating the handle 45 the chain 42 is moved in either direction and the sprocket wheel 40 simultaneously rotated; whereby 20 the frame 10 is adjusted vertically on the posts. For locking the parts in adjusted position an idle sprocket 50 is loosely mounted on a post 51 so as to mesh with the sprocket 49. A thumb nut 52 is threaded on the post 25 and when tightened fastens the sprocket 50 against rotation thus also locking the sprocket 49 against rotation.

Within the handle 45 which is not rotatable, a suitable electric switch 53 is mounted and provided with a plunger 54 projecting thru the wall of the handle. An electric cable 55 leads into and thru the handle to the switch 53 while a second cable 56 leads from the switch to the motor and is suitably 35 connected thereto, the details of construction of the motor not being illustrated or described. It will be seen that the operator may turn the handle 44 with one hand and adjust the machine and may operate the 40 switch with the other hand, so that the machine is at all times entirely under his control.

The vase 39 constitutes an elongated plate member having an opening 57 at its central portion thru which the drum projects to engage the work. The base also has shoes or runners 58 of cloth or any suitable material stretched over its bottom surface on each

side of the drum and suitably fastened, the particular construction of the same being 50 covered by a separate application filed January 13, 1920, Serial No. 351,156. It is to be understood that the posts 38 could be mounted on any suitable kind of a base.

In using the machine the operator grasps 55 the handles 44 and 45 and depresses the plunger 54 so as to start the motor. By rotating the handle 44, the chain 42 is caused to travel thereby turning the sprockets 40 which ride up or down on the posts 38 according to the direction in which the handle 44 is rotated. The frame being attached or supported on the sprockets 40 is adjusted vertically whereby the drum 18 is moved toward or from the work thru the slot 57 in the base 65 39. It will be seen that a very minute adjustment may be had and the drum may be adjusted while the machine is in operation. The sand paper 19 may be easily replaced when necessary.

What I claim, is:

In a machine of the character described, a frame having a horizontal transverse chamber formed integral within the upper end thereof, said chamber having its wall formed 75 imperforate and provided in its lower portion with an opening, a horizontal bracket secured to the lower portion of said wall and extending into said opening, plates detachably held within the ends of the chamber, 80 bearing devices carried by said plates, a motor mounted in the chamber and embodying an armature shaft journaled in said bearing devices, a rotating surface treating element rotatably mounted within the lower portion of said frame, a gear mounted upon the surface treating element and arranged within said frame, an intermediate gear arranged within said opening within the frame and mounted upon said horizontal bracket, a gear mounted upon the armature shaft and arranged within said chamber and engaging the intermediate gear, and 85 supporting means for the frame.

In testimony whereof I affix my signature. 90
ALEX A. CLARKE.
